(57) **CLAIM**

The ornamental design for a carrier with stroller body, as shown and described.

DESCRIPTION

FIG. 1 is a top, front, right perspective view of a first embodiment of a carrier with stroller body in accordance with our design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom view thereof.

FIG. 8 is a top, front, right perspective view of a second embodiment of a carrier with stroller body in accordance with our design;

FIG. 9 is a front elevational view thereof;

FIG. 10 is a rear elevational view thereof;

FIG. 11 is a right side elevational view thereof;

FIG. 12 is a left side elevational view thereof;

FIG. 13 is a top plan view thereof; and,

FIG. 14 is a bottom view thereof.

The broken lines in the drawings are for the purpose of illustrating portions of the carrier with stroller body and form no part of the claimed design.

1 Claim, 14 Drawing Sheets
